COMBINED RELIEF VALVE AND WATER DISTRIBUTION MANIFOLD

Jack A. Britton, Lakewood, Ohio

Application October 17, 1955, Serial No. 38,400

Term of patent 14 years

(Cl. D91—3)

Figure 1 is a front elevational view of a combined relief valve and water distribution manifold showing my new design;

Figure 2 is a side elevational view; and

Figure 3 is a top view.

I claim:

The ornamental design for a combined relief valve and water distribution manifold, substantially as shown.
